[57] **CLAIM**

The ornamental design for a personal computer keyboard template for displaying operating instructions for software program, as shown and described.

DESCRIPTION

FIG. 1 is a front, top and left side perspective view of a personal computer keyboard template for displaying operating instructions for software program showing my new design, the keyboard being shown in broken lines for illustrative purposes only;

FIG. 2 is a top plan view thereof on an enlarged scale;

FIG. 3 is a front elevational view thereof on an enlarged scale;

FIG. 4 is a bottom plan view thereof on an enlarged scale;

FIG. 5 is a left side elevational view thereof on an enlarged scale;

FIG. 6 is a right side elevational view thereof on an enlarged scale.

FIG. 1.

FIG. 2.

FIG. 3.

FIG. 4.

FIG. 5.

FIG. 6.
